(57) **CLAIM**

The ornamental design for a lamp, as shown and described.

DESCRIPTION

1. Lamp
- 1.1 : Perspective
- 1.2 : Perspective
- 1.3 : Front
- 1.4 : Top
- 1.5 : Bottom

The broken lines in the drawings illustrate portions of the lamp and break lines which form no part of the claimed design; the break lines in figures indicate that the appearance of any portion of the lamp between the break lines forms no part of the claimed design.
